UNITED STATES PATENT OFFICE.

LEO SEIDL AND ARMIN KRAUSZ, OF BROOKLYN, NEW YORK.

DENTAL HANDPIECE SPRAY.

Application filed February 3, 1925. Serial No. 6,548.

This invention relates broadly to improvements in dental hand-pieces, and more particularly to an attachment for dental hand-pieces, whereby the usual stone wheel is supplied with moisture.

At the present time there are devices for supplying moisture to the stone-wheel used in conjunction with a dental hand-piece, but these apparently fail to afford the proper necessities, and to take into consideration the following requirements.

In operating a hand-piece with a grinding element such as a stone-wheel the dentist must use the thumb, first and second fingers of one hand to obtain the proper and recognized grip on the hand-piece, depending on the other fingers of the same hand to obtain a proper rest. The fingers of his other hand are used to hold the cheek or lip 20 of the patient away from contact with the machine or tooth being operated upon. It is also necessary to point out that a stone-wheel is used with three motions, namely, push motion, pull motion, and cutting motion. Opposite sides of the stone-wheel are used for the first two motions, and the edge for the third. At the present day also, hand-pieces of the straight type are not always used, but the contra-angle attachment is 25 placed into use on the hand-piece, and the stone-wheel is carried on the mandrel of the contra-angle attachment operating in a different plane than on the straight hand piece.

It will therefore be apparent at the start, 30 that to have an efficient spray for dental hand-pieces it is necessary that the same does not prohibit the accustomed and recognized use of the fingers; that it supply all surfaces of a stone-wheel with moisture; and that it be readily applicable to all types of hand pieces.

The objects of the present invention are to afford a device meeting the foregoing requirements and overcoming the objections 45 to the devices for the same purpose.

Other objects and advantages of the invention will be apparent during the course of the following description, throughout which reference is made to the accompanying drawings forming a part of this specification, and in which,

Figure 1, is a top plan view of a dental hand-piece with an attachment embodying the invention applied thereto, and illustrating 50 the application and use of the invention;

Fig. 2 is a side elevation of an apparatus embodying the invention; and

Fig. 3, is a sectional view taken approximately on the line 3—3 of Fig. 2.

Referring to the drawings, wherein for the purpose of illustration is shown a preferred embodiment of the invention, the numeral 5 designates the usual dental hand-piece having a pulley wheel 6, to which is applied the cord 7 which is also connected to a dental engine, and by which the mandrel 8 carrying the stone-wheel 9 is rotated. These parts are all of standard use and form no part of the present invention in themselves.

A preferably rigid tube 10 is connected to the hand-piece 5, by means of bands 11, other suitable means being used if desired, so long as the tube 10 can be readily disengaged from the hand-piece. The tube 10 is connected at one end to a flexible tube 12 leading from any suitable source of water supply, and to the other end of the tube 10 is connected a nozzle 13. A valve 14 is mounted in the tube 10, and is operated by means of the handle 15 to control the flow of water therethru.

The nozzle 13 is revolvably mounted in one end of the tube 10 by the tubular extension 16 of the said nozzle which fits into the closed end of the tube 10 as illustrated in detail in Fig. 3, so that the nozzle 13 can be rotated to any desired position with respect to the tube 10, and secured in the desired position by means of the set-screw 17. The nozzle is preferably formed with two spray jets 18 and 18^a having oppositely disposed constricted openings, so that water is supplied to each side of the stone-wheel. It will be noted by reference to the drawings that the jet 18 is formed by the constricted straight end of the nozzle 13, while the jet 18^a by a substantially U shaped extension coming off of the nozzle proper adjacent the jet 18, and that the arms of the said U shaped extension forming the jet 18^a embrace the stone-wheel 9 when the nozzle is in position to supply water to the stone-wheel, as illustrated in the full line positions of the nozzle in the drawings.

By reference to Fig. 2 of the drawings, it will be noted that the nozzle 13 can be swung on its pivoted extension 16, into a position clear of the stone-wheel 9 and the mandrel 8, as indicated in dotted lines. The nozzle

is readily swung into this position and secured there through the set-screw 17, when the operator does not desire to use the same.

Figure 1 illustrates the proper grip on a dental hand-piece, and it will be observed that the valve handle 15 is in close proximity to the thumb of the hand in which the hand-piece is held, and therefore, by a slight movement of the thumb can be quickly operated to regulate or control the flow of water thru the tube 10, nozzle 13 and jets 18 and 18^a. It may be preferable to use the other hand to operate the valve handle 15, and as the fingers of such hand are naturally being used to hold the part of the patient's face adjacent the tooth being operated upon, the use of one of the fingers to touch the valve handle necessitates no stopping of work; or relinquishing grip on the hand-piece.

In operation, the spraying attachment is applied to the hand piece detachably but securely by means of the clamping band 11. When a stone-wheel is placed into the hand-piece and is to be used, the nozzle 13 is swung into the full line positions indicated in Figures 1 and 2. The operator then grips the hand-piece, and by turning the valve-handle to the dotted line position indicated in Figure 1 in any of the manners above mentioned, allows water to flow thru the tube 10, extension 16, nozzle 13, and jets 18 and 18^a on to both sides of the stone-wheel 9. The flow of water can be controlled and regulated by the valve handle 15 at any time. Due to the fact that both sides of the stone-wheel are sprayed, and naturally some of the moisture runs onto the edge of the wheel, all surfaces of the wheel are kept moist, and the wheel greatly cooled.

It will be apparent that the invention is just as effective when a contra-angle attachment is placed on the hand piece, for the nozzle 13 can be swung into position relative to a stone-wheel at any point in its path of motion on its pivot 16. While it is true that some contra-angle attachments will lengthen the distance of the stone-wheel from the end of the hand-piece proper, it must be remembered that the spraying de-

vice is detachably connected to the hand piece and can be moved longitudinally with respect to the hand-piece.

It is obvious that many changes might be resorted to in the construction and assembling of the several parts without departing from the spirit of the invention or scope of the appended claims, we desire to point out that the size, shape and arrangement of the several parts are matters of choice reserved to us; also that more than two spray jets might be used without departing from the invention or scope of the claims.

We claim as our invention:

1. A spray device for dental stone-wheels comprising, a tubular member for connection with a source of water supply, water flow controlling means associated therewith, a nozzle associated with said tubular member and angularly adjustable with respect thereto, and a plurality of oppositely disposed spray jets carried by said nozzle.

2. A nozzle for dental stone-wheel spraying apparatus comprising, a body member for attachment to a source of water supply on a hand piece, a plurality of oppositely disposed spray jets carried by said body member, one of said jets being formed by a U shaped extension of the body member, and all of said jets being angularly adjustable with the nozzle with respect to the hand piece and instruments mounted in the hand piece by movement of the body member.

3. A spraying attachment for dental hand-pieces comprising a tubular member for attachment to the hand-piece, a nozzle, a tubular extension on said nozzle rotatably mounted in the first tubular member and communicating with the interiors of the first tubular member and nozzle, oppositely disposed spray jets formed at the end of said nozzle and adjustably rotatable therewith on the tubular extension, and means for maintaining said nozzle and spray jets in desired position with respect to the hand piece and instruments mounted therein.

In testimony whereof we affix our signatures:

LEO SEIDL.
ARMIN KRAUSZ.
